COMBINED BRUSH AND COMB

James Tucker, Chicago, Ill., assignor to The Gillette Company, Boston, Mass.

Filed Sept. 10, 1969, Ser. No. 19,089

Term of patent 14 years

Int. Cl. D28—03

U.S. Cl. D86—8

FIG. 1 is a side elevational view of a combined brush and comb showing my new design; the side opposite being substantially similar thereto;

FIG. 2 is an end view;

FIG. 3 is a view in section along line 3—3 of FIG. 1;

FIG. 4 is a view in section along line 4—4 of FIG. 1; and

FIG. 5 is a view in section along line 5—5 of FIG. 1.

I claim:

The ornamental design for a combined brush and comb, as shown and described.
